UNITED STATES PATENT OFFICE

EINAR MORTERUD, OF TORDEROD, NEAR MOSS, NORWAY

PULP DIGESTER WITH INTERIOR CIRCULATION

Application filed October 10, 1929. Serial No. 398,750.

The present invention relates to pulp digesters having an interior circulation system, and the object of the invention is to provide a circulation system of this kind which will be simple, cheap and effective, and which will not in any way form an obstruction to the digested pulp when the same is to be removed from the digester.

In accordance with the invention these objects are attained by means of a circulation system comprising a substantially straight tubular intake sieve, a circulation pump, a tubular heating chamber for heating the liquor or liquid by means of directly introduced steam, and an outlet sieve communicating with the heating chamber.

The pump may or may not be reversible, in which latter case it will be obvious that the intake sieve will be adapted to act also as outlet sieve and vice versa.

On the drawing Fig. 1 is a side view with one part in vertical section of a digester provided with a circulation system in accordance with the present invention.

Fig. 2 is a detail showing the circulation system as seen from the inside of the digester.

The circulation system comprises a pump 1, which may be of the reversible or ordinary type, and which is secured to the shell 2 of the digester in some convenient manner.

The suction side of pump 1 communicates with an interior sieve 3, which is in the form of an approximately straight tubular member having its lower end adjacent the apex of the conical bottom section 4 of the digester, and extending along the inside of the said bottom in such a manner as to form no obstruction to the digested pulp when the same is to be removed through the bottom opening 5 of the digester.

The outlet side of the pump communicates with a tubular heating chamber 6, which is secured to the digester shell at a point between its ends by means of a tubular shank 7. Through this tubular shank passes a steam inlet pipe 8, which communicates inside the heating chamber 6 with a steam introduction pipe 9 located coaxially with the tubular heating chamber 6.

At its upper end the tubular heating chamber 6 communicates with an outlet sieve 10, which may be of approximately the same type as inlet sieve 3 conforming more or less accurately to the curvature of the inner top 55 wall of the digester.

As it has been stated, pump 1 may be a reversible pump, in which case sieve 10 will act as intake sieve and sieve 3 as outlet sieve.

Claim:

In a pulp digester a heating chamber comprising a tubular member located along the inner wall of the digester near the central part thereof, a tubular shank attached to the said tubular member between its ends for securing the same to the digester shell, a steam introduction tube passing through said tubular shank to the interior of the said tubular heating chamber, a circulation pump communicating with one end of said heating chamber and an outlet sieve communicating with the other end of said heating chamber.

In testimony whereof, I affix my signature.

EINAR MORTERUD.
